UNITED STATES PATENT OFFICE.

HARVEY S. COOK, OF BOSTON, MASSACHUSETTS.

BED.

SPECIFICATION forming part of Letters Patent No. 310,255, dated January 6, 1885.

Application filed December 31, 1883. (No model.)

To all whom it may concern:

Be it known that I, HARVEY S. COOK, of Boston, in the county of Suffolk, State of Massachusetts, have invented a certain new and useful Improvement in Mantel-Bedsteads, of which the following is a description sufficiently full, clear, and exact to enable any person skilled in the art or science to which said invention appertains to make and use 10 the same, reference being had to the accompanying drawings, forming a part of this specification, in which—

Figure 1 is an isometrical perspective view representing my improved bedstead opened 15 or let down for use, and Fig. 2 a vertical transverse section of the same.

Like letters and figures of reference indicate corresponding parts in the different figures of the drawings.

20 The object of this invention is to provide an economical structure which will serve the double functions of a mantel and a bedstead.

The nature and operation of the improvement will be readily understood by all 25 conversant with such matters from the following explanation, its extreme simplicity rendering an elaborate description unnecessary.

In the drawings, A represents the casing, and B the frame or bedstead proper. The casing 30 may be portable, or may be permanently fixed in the room, as desired, and consists of the bottom C, upright ends D, and top or mantel E, the top being provided with a back, G.

The bedstead proper consists of the side 35 rails, H H, and end rails, J J, which are properly and permanently framed together, as shown.

Arranged horizontally in the ends D, and 40 passing through the end rails, J, near their inner ends, is a rod, K, on which the frame B is pivoted or journaled, this rod also serving in place of legs for the support of the rear side of said frame. A fixed auxiliary supporting and stop rod, L, is also supported in 45 the ends D, this rod being arranged parallel with the rod K, and disposed below the rails J, but nearer the front edges of said ends than the rod K, so that the frame may be readily turned up when the bed is not in use. A rod, 50 M, is also journaled horizontally in the outer ends of the rails J in parallelism with the rods K L, its ends being elongated and bent downwardly to form the legs N N. The fixed rod L is bent downward at its center, forming a 55 looped arm, m, and the rod M is also bent

downward at its center, forming a crank, m', opposite the arm m of the rod L. A link, P, connects the arm m and crank m', being jointed so as to move freely thereon.

In the use of my improved bedstead, as the 60 frame B is let down or into the position shown in Fig. 1, the arm m of the rod L being immovable, the link P, attached thereto by its inner end, will act upon the crank m' of the rod M to partially rotate said last-named rod 65 and bring the legs N into a vertical position as they touch the floor, or when the rails J arrive at a horizontal position, in a manner which will be readily obvious without a more explicit description.

In folding the frame B into the body or case A when the bed is not in use, as the outer rail, H, rises the rod P will depress the crank m' of the rod M, thereby partially rotating 70 said rod and causing the legs N to be turned inwardly against the sides of the rails J.

When the frame B is turned up and closed, its lower side rests against the auxiliary supporting and stop rod L, whereby said frame 75 is held in upright position and prevented from falling against and marring the wall, as would be the case when the back is not boarded up. This rod serves also as an auxiliary support for the bed-frame when open.

The frame B is provided with a sack, f, for 80 supporting a mattress; but any other means for this purpose may be employed.

A curtain may also be employed for concealing the frame when it is folded into the case.

Having thus explained my invention, what I 90 claim is—

The combination, in a mantel-bedstead, of a casing provided with a mantel, a supporting-rod extending between the ends of said casing, a swinging bed-frame supported at its inner side by said rod, and pivoted to swing thereon, a fixed rod extending between the ends of said casing in front of said supporting-rod, and provided with a downward-bent 95 arm, a swiveling rod having its bearings in the end rails of said bed-frame, near the outer side thereof, said swiveling rod being provided with legs at its outer ends and with an intermediate crank, and a link connecting 100 said arm of the fixed rod with said crank of the swiveling rod, substantially as described.
